UNITED STATES PATENT OFFICE.

LAWRENCE J. LESH, OF NEW YORK, N. Y., ASSIGNOR TO EMIL J. SIMON, OF NEW YORK, N. Y.

SPARK-GAP APPARATUS.

Application filed April 9, 1918. Serial No. 227,440.

To all whom it may concern:

Be it known that I, LAWRENCE J. LESH, a citizen of the United States, residing at New York city, in the county of New York and State of New York, have invented certain new and useful Improvements in Spark-Gap Apparatus, fully described and represented in the following specification and the accompanying drawings, forming a part 10 of the same.

This invention relates especially to spark gap apparatus for use in radio transmitting and receiving sets, the invention not being confined in all its features, however, to 15 spark gap apparatus. More particularly the invention relates to spark gap apparatus of the multiple unit gap type, and the invention aims generally to provide improved apparatus of this type of a simple 20 and compact construction and which shall provide for convenient and ready removal and replacement of the spark gap units and for convenient adjustment of the circuit for connecting any desired number of the units 25 and any desired group of the units in the circuit, and to provide an improved spark gap unit. The invention consists in the features of construction, arrangement and combinations of parts herein disclosed and 30 specifically pointed out in the claims.

As a full understanding of the invention can best be given by a detail description of an approved construction embodying the 35 various features of the invention and certain modifications thereof, such a description will now be given in connection with the accompanying drawings, in which:—

Fig. 1 is a view in front elevation of a 40 multiple unit spark gap apparatus made in accordance with the invention, only part of the whole number of spark gap units being shown in position in the holders;

Fig. 2 is a section taken on a horizontal 45 plane indicated by the line 2—2 on Fig. 1;

Fig. 3 is a side view of the apparatus with the contact arms in a different position from that shown in Figs. 1, 2 and 4;

Fig. 4 is a partial rear view of the 50 apparatus showing the adjustable contact arms and the contact knobs which are connected with the gap holders, the contact arms being in the position of Figs. 1 and 2;

Figs. 5, 6 and 7 are detail sectional views 55 illustrating the action of the contact pieces carried by the contact arms;

Fig. 8 is a face view of the inner face of a gap plate of one of the unit spark gaps;

Fig. 9 is a central sectional view of one of the unit spark gaps; and

Fig. 10 is an edge view of a spark gap 60 unit provided with heat dissipating ribs.

Referring to the drawings, and first to Figs. 1 to 7, the apparatus shown comprises a plurality of unit spark gaps 10, and holding and circuit controlling apparatus therefor. The parts of the apparatus are mounted on a support 11 which is most desirably in the form of a flat board or plate of bakelite delecto or other suitable insulating material and which is usually mounted in vertical position on the instrument board either in or opposite an opening through which portions of the apparatus extending from the rear side of the support may extend beyond the rear side of the instrument board. 70 The support is most desirably mounted on the instrument board so that it may be readily moved to give access to parts of the apparatus on the rear side of the support, and for this purpose the support in the construction shown has at its lower edge a hinge connection to the instrument board, as indicated at 12, so that it may be swung forward and downward from the position shown in Figs. 1 and 3, being normally held 75 in operative position by a suitable catch or holding means 13.

The unit spark gaps may be of any suitable construction, for example, as shown in U. S. Patent No. 1,253,103 granted to E. J. 90 Simon January 8, 1918. Most desirably, spark gaps embodying the features of the invention as illustrated by the gap shown in Figs. 8 and 9 are employed.

The gap shown in these figures, which is a single 95 sparking space unit, although features of the invention embodied therein are obviously not limited to a single sparking space, or two-plate, gap, comprises two flat electrode plates 15 and 16 of heat-conducting and electricity-conducting material which may be of circular or other suitable form, each plate being formed at its inner face with a flat central seat to which is secured an electrode or sparking plate 17 and with an annular bearing face 18 surrounding the electrode and separated therefrom desirably by an annular channel 19. The plates are secured together with an annular gasket 20 of fish paper impregnated with 100 105 110

linseed oil and beeswax or other suitable insulating and air-excluding material, between their bearing faces by means of screw bolts 21, each of which is screwed into one of the plates and has its head seated in a bushing 22 of insulating material seated on the other plate. The bearing faces of the gap plates are desirably grooved to provide one or more narrow annular ribs 23, which, bearing against the gasket 20, increase the assurance of exclusion of air from the sparking space. The electrodes 17 may be riveted or otherwise secured to the electrode seats of the gap plates and in the assembled gap have their sparking faces parallel and spaced slightly apart to provide the necessary sparking space between them.

It will be noticed that in the construction shown the screw bolts 21 by which the gap plates are forced and held pressed against the interposed gasket 20 to set the plates the proper distance apart and to form the airtight joint are located inside, or within, the outer portions of the bearing faces 18. By thus locating or arranging the clamping devices to exert their pressure on the plates at a point or points within the outer portions of the bearing faces of the plates and interposed gasket, the difficulty which has been experienced in assembling the plates of spark gaps in which the clamping devices exert their pressure outside of or beyond the outer circumferential portions of the bearing faces of the plates is avoided. With my construction, the tightness with which any one of the screw bolts 21 is set to hold the adjacent portions of the plates together is not affected by the tightening or loosening of any other of the screw bolts. Most desirably, in order to avoid the possibility of access of air to the sparking space through the screw bolt openings, the screw bolts are located with relation to the bearing faces so that the bearing faces extend inside of as well as outside of the screw bolts, thus providing a continuous seal between the sparking space and the screw bolts.

The center of the electrodes proper, or sparking plates, is most desirably removed so as to provide sparking plates and sparking surfaces of annular form, as shown in Figs. 8 and 9. I have found that the use of such annular electrodes results in the voltage remaining constant under a longer continued operation than when the center of the electrodes is not removed. This improved result is probably due to the fact that the use of sparking plates of this form avoids, or at least reduces, the warping or buckling of the plates resulting from the action of heat on metals of dissimilar coefficients of expansion, and also possibly to the better discharge of heat from the plates. The sparking plates or electrodes should be

made from a metal of high thermal and electrical conductivity, plates of silver being usually used. The gap plates on which the electrodes are mounted are usually made of brass or other metal of suitable strength and not too expensive.

Extending from the face of the support 11 are a plurality of holders, each adapted to receive and hold a single spark gap unit. Each holder comprises a pair of spring conducting arms 25 and 26 for bearing on opposite sides of the spark gap unit, the arms being desirably formed with knobs or bosses to extend into recesses 27 formed in the gap plates for more securely holding the gap while yet permitting its ready removal and replacement when desired and the outer ends of the arms of each holder are bent outwardly to permit the gap unit to be more readily entered between them. The electrical connections to the gap units when in position in the holders are made through the holder arms, and the holders are connected in series, the adjacent arms of adjoining holders being electrically connected, as by forming such adjacent arms of adjoining holders of a single piece of metal bent into U form, the connecting portion of the metal, or plate 28, between the two arms providing means for conveniently securing the arms to the support 11 by means of screws as shown. The arms of each holder are insulated from each other when a gap is in position between them except for the sparking action across the gap. When all the holders are provided with spark gap units fitted therein, the gap units carried by a series of holders so arranged will, therefore, be electrically connected in series. In order that the series connection shall not be broken by the removal of any one or more spark gap units, the holders are so formed that on the removal of the spark gap unit from any holder the circuit will be closed between the two supporting arms of the holder, this result being secured in the construction shown by having the holder arms set under such spring tension that the arms of each holder will bear against each other when there is nothing interposed between them. The outer arm of the end holder of each row of holders is secured to the support by means of a flange or plate 28^a at its inner end screwed or otherwise secured to the support.

In the construction shown in Figs. 1, 2 and 3, the holders are arranged to support the spark gap units in two parallel series or rows, the gap units being supported to stand vertically and perpendicular to the support 11 in horizontal rows, one above the other. This arrangement of the gap holders to support the gap units in rows or series in which the units stand flatwise to each other and spaced apart has the advantage that it provides for the free move-

ment of air between the gap units and consequent cooling of the units; and having the holders arranged to so support the gap units vertically in horizontal rows has the further advantage that as the units become heated an upward flow of air between them is induced.

For further providing against an undue increase in temperature of the spark gap units in operation, the outer surface of the gap plates is desirably formed with parallel ribs 29 to provide an increased heat dissipating surface, as shown on one of the gap units in Fig. 3 and on the gap unit shown in Fig. 10. The gap units should be placed in the holders turned so that these cooling ribs extend vertically, and in order that the ribs shall not interfere with the placing of the gap units in the holders and their removal therefrom, the ribs are cut away at the center of the gap plates and in a path extending from the center radially outward to the edge of the plates, as appears from Fig. 3.

In order that circuit connections may be made to include in the operating circuit any desired number of the holders and spark gap units carried thereby, connection is made from each of the plates or portions 28 and 28^a by means of a connector 30 to one of a series of contact terminals 31, each plate 28 and 28^a being connected to its own corresponding terminal, except that the plate 28^a at the right hand end of the upper row 35 of holders is connected to the same terminal as the plate 28^a at the right hand end of the lower row of terminals, this connection thus serving to connect the outer arm of the right hand end holder of the upper row with the outer arm of the corresponding end holder of the lower row, so that the two rows of holders are thereby connected in a single series, these two holder arms of what are in effect adjoining holders being thus connected 45 to a single contact terminal in the same manner that adjacent arms of other adjoining holders of the series are connected to a single contact terminal. The outer arms of the end holders at the left hand end of the two rows, which holders are the end holders of the whole series, are connected to separate terminals 31.

The terminals 31 are arranged in a circular series on the rear side of the support 11, and 55 in the construction shown are of ball or rounded knob form, having stems extending through the support 11 to connect with the respective connectors 30, the support being formed, as before stated, of a plate of suitable insulating material. The means which I provide for making connection to the gap holders through the terminals 31 and for varying such connections, is arranged to permit not only of variation in the number of 65 gaps connected in the operating circuit, but

also when less than the whole number of gaps is so connected to permit of so connecting in the circuit any desired group of gaps. In the embodiment of this feature of the invention shown, I provide two contact arms 70 35 and 36 mounted to swing about a common axis located centrally of the series of contact terminals 31, and means for swinging said arms either separately or together.

The contact arm 35 is carried by a hollow shaft 37 which extends through the support 11 and is journaled at its forward or front end in a cross-bar 38 carried by side pieces 39 extending forward from the support 11. The contact arm 36 is carried by a shaft 40 which extends through and is fitted to turn within the shaft 37. The shaft 37 carries at its outer end in front of the cross-bar 38 a hand wheel 41 by which the shaft and the contact arm 35 may be turned; and the shaft 80 40 carries at its outer end in front of the wheel 41 a hand wheel 42 by which the shaft 40 and the contact arm 36 may be turned. The contact arms 35 and 36 are made of conducting material and are insulated from 90 each other in the construction shown by forming the shaft 40 of bakelite delecto or other suitable non-conducting material. The shaft 37 is also in the construction shown and most desirably made of non-conducting 95 material. The shaft 37 has surrounding its rear end a metal collar 45 provided with an end flange from which the arm 35 extends. This collar 45 extends into a bearing ring 46 secured in a central opening in the supporting plate 11. From the bearing ring 46 connection is made by a conductor 47 to a conducting rod 48 extending through and to the rear of the support 11 and carrying a terminal 49. For securing good contact with the 105 bearing ring 46, the conductor 47 is formed with a ring which surrounds the shaft 37 and is screwed or otherwise secured to the end of the bearing ring 46. Connection from one side of the circuit is made to the terminal 49 and from the other side of the circuit directly to the arm 36.

In order that circuit connections to the terminal 49 and the contact arm 36 may be automatically made by the act of placing the support 11 in position for operation of the device and broken by removing the support from such position, that is, in the construction shown, by swinging the support into the position shown in Figs. 1 and 3 or forward 110 and downward from such position in order to give access to parts of the apparatus on the rear side of the support, yielding contact pieces 50 and 51 are provided mounted 115 in position to make contact with the terminal 49 and with the arm 36 respectively when the apparatus is in operative position. These contact making parts are most desirably of ball and cup form as shown, the contact pieces 50 and 51 having recessed con- 120 125 130

tact faces, and the terminal 49 being shaped to fit the recess of the contact 50 and the arm 36 having its hub or axial portion 52 formed to provide a terminal shaped to fit the recess of the contact piece 51. The contact pieces 50 and 51 in the construction shown are carried by spring pressed rods mounted in housings 53 and 54 respectively, carried by posts 55, one of which is shown in Fig. 3, to the base of which posts the circuit wires 56 and 57 are connected.

The contact arms 35 and 36 carry each a spring pressed contact piece 60 and 61 respectively for making contact with the terminal knobs or balls 31. The contact piece 60 is carried by a spring pressed rod mounted in a housing 62 carried by arm 35, and the contact piece 61 is carried by a spring pressed rod mounted in a similar housing 63 carried by the arm 36. Each of the contact pieces 60 and 61 is formed with a concave or cup-shaped bearing face to fit down over the convex outer faces of the terminals 31 so as to give an extended contact and also so that the contact piece thus formed and spring pressed shall serve to accurately position the contact piece with respect to any terminal 31 and yieldingly resist turning movement of the contact arm from any position of contact. The contact pieces and the terminals being formed with co-acting positioning faces, will thus serve to indicate manually to the operator turning the wheels 41 or 42 when either arm has been moved into position to bring its contact piece into register with and proper contact relation with any desired terminal 31.

In order that the slight resistance to turning of the wheels 41 and 42 which serves as a manual indication of correct position of the contact arms shall occur only when an arm has been moved to bring its contact piece into register and proper contact relation with one of the terminals 31, the contact pieces 60 and 61 are so formed with regard to the relative position or spacing of the terminals 31 that when one of the contact pieces has been pushed back by the turning movement of its arm to carry it from engagement with one of the terminals into engagement with an adjacent terminal, it will come into engagement with the adjacent terminal while still held against forward movement by engagement with the terminal 31 from which it is being moved.

Referring to Figs. 5, 6 and 7, Fig. 5 shows a contact piece 60 in engagement with a terminal 31. Fig. 6 shows the position of the contact piece when the arm 35 has been moved to carry the contact piece half the distance for bringing it into engagement with an adjacent terminal. In this position the contact piece has been pressed back against the pressure of its spring by riding up on the face of the terminal, the contact

piece being held in this position by engagement at one side with a high point of the terminal from which it is being moved and having also come into engagement on its other side with a high point of the terminal into contact forming engagement with which it is being moved. By continued movement of its carrying arm, the contact piece is then carried on over the new terminal, and as it moves over such terminal is advanced by its spring until it is brought into the desired contact forming relation with the new terminal as shown in Fig. 7. The pressure of the contact piece against the inclined face of the far side of the terminal after it has been moved somewhat from the position shown in Fig. 6 serves to aid in the completion of its positioning movement and insures its reaching the desired position from which further forward movement is then resisted by the engagement between the inclined faces of the contact piece and terminal. In this shifting movement of the contact piece from one terminal to an adjacent terminal no forward movement of the contact piece in the space between the terminals has been permitted, and, therefore, no resistance to the turning of the contact arm takes place except when the contact piece is positioned properly with respect to one of the terminals 31. The operator in turning either one of the hand wheels 41 or 42 can, therefore, always tell from the turning resistance of its hand wheel when either of the contact pieces is in proper engaging position with one of the terminals.

A distance piece 65 extending from the shaft 40 to the housing 63 carried by the contact arm 36 and formed of or having an engaging portion of insulating material serves by engagement with the end of the arm 35 to limit the approaching movement of the two arms. The engaging portion 66 of this distance piece may be formed to extend to any desired extent according to the minimum distance to which the approaching movement of the two arms is to be limited. As shown, see Fig. 4, the engaging portion 66 is so formed that when the arms have been moved toward each other to the limit of their approaching movement there will be one terminal 31 between the engaged terminals; that is, so that there must always be at least two spark gap holders included in the operating circuit. The distance piece 65 in the construction shown serves also as a steadyng arm for the sleeve 63, which is supported by the arm 36 at a point near its rear end. A stop 67 formed in the construction shown by a stud extending rearward from the supporting plate 11 serves to prevent movement of the contact arms 35 and 36 beyond their respective positions for engagement with the respective end terminals 31 of the series.

When the contact arms 35 and 36 are in the positions shown by Figs. 1, 2 and 4, the

eight gap holders of the upper row will be connected in the spark gap circuit, the circuit then extending from the wire 56 through the spring contact piece 50, terminal 49, rod 48, connector 47, arm 35 and its contact piece 60 to the terminal 31 which is connected to the outer arm of the gap holder at the left-hand end of the upper row of holders, viewing the same from the front of the apparatus as it appears in Fig. 1; thence through the upper row of holders and spark gaps held thereby to the outer arm of the holder at the right-hand end of the upper row, from which the circuit extends through its connector 30 to its terminal 31 with which the contact piece 61 is in engagement; and thence through the contact piece 61, arm 36, spring contact 51 and its housing and post to the circuit wire 57. If the gap holders of the upper row are each provided with a gap unit, there will thus be eight gap units connected in series. If one or more of the holders is not provided with a gap unit, the units in the remaining holders of the upper row will nevertheless be connected in series in the circuit, the circuit being then completed across the empty holders by engagement of their spring holding arms.

By turning the arm 36 in either direction from the position shown in Figs. 2 and 4 while the arm 35 remains stationary, the number of gap holders connected in the circuit may be increased or decreased according to the direction in which the arm 36 is turned; and if the arm 35 be turned while the arm 36 remains stationary, the number of holders connected in the circuit will also be correspondingly changed. By turning both arms together without changing their relative angular relation, the connections will be shifted so as to change the particular series or group of gap holders included in the circuit without changing the number of holders included. The desired shifting of the contact arms either relatively or together is readily accomplished by means of the hand wheels 41 and 42, the resistance or feel of the wheels indicating to the operator when the contact arms are in proper contact making position, as already explained.

In order to aid the operator in making the desired adjustment of the gap connections, suitable position indicating means for indicating visually the position of the contact arms is desirably provided in connection with the hand wheels 41 and 42. In the construction shown, such means comprises an indicating disc 70 which is mounted in front of the cross piece 38 and to the rear of the hand wheel 41 and connected to turn with the hand wheel 41 and shaft 37. This disc is marked with an arrow and a series of numbers arranged circumferentially thereon corresponding to the number of gap holders; and the front hand wheel 42 is pro-

vided with an indicating mark shown as having an arrow associated with it. The arrows on the disc 70 and on the hand wheel 42 are so placed relatively to the contact arms controlled by the two hand wheels that the relative position of the arrows will indicate at all times the relative positions of the contact arms; and the numbers on the disc 70 are spaced according to the spacing of the contact terminals 31 so that the position of the arrow or other mark on the wheel 42 with relation to the numbers on the disc 70 will indicate the number of gap holders connected in the circuit. For example, when the contact arms are in the position shown in Figs. 2 and 4, in which 8 gap holders are connected in the circuit, the mark on the hand wheel 42 will indicate the number 8 on the disc 70. If one or the other of the hand wheels is turned to move its contact arm relatively to the other contact arm so as to connect a greater or less number of gap holders in the circuit, such greater or less number will then be indicated by the position of the mark on the hand wheel 42 with relation to the number series on the disc 70. If the two hand wheels be moved together so as to shift the contact arms without changing the number of gap holders connected in the circuit, the relation of the indicating mark on the hand wheel 42 to the number series on the disc will not change, but the shifting of the disc and the position of the series of numbers between the arrow on the disc and the indicating mark on the wheel 42 will indicate the location of the series or group of gap holders connected in the circuit.

While in the construction shown the gap unit holders are connected in the circuit in series, the feature of the invention relating to the selective connection of the holders in the circuit is obviously not limited in its application merely to arrangements in which the holders are connected in the circuit in series-connected groups; and it is also to be understood that this selective connection feature of the invention is not limited to spark gap units as the only electrical elements for the selective connection of which it may be employed.

What is claimed is:

1. A spark gap unit, comprising a plurality of electrode plates assembled together flatwise with their sparking faces spaced apart to provide a spark gap space between them, said plates having bearing faces extending about their sparking faces and being secured together with an insulating and air excluding packing between their bearing faces by a plurality of clamping devices arranged about the sparking faces of the plates but within the outer portions of their bearing faces.

2. A spark gap unit, comprising a plurality of electrode plates assembled together

- flatwise with their sparking faces spaced apart to provide a spark gap space between them, said plates having bearing faces extending about their sparking faces and being secured together with an insulating and air excluding packing between their bearing faces by screw bolts located in holes in the plates opening through their bearing faces at points intermediate the inner and outer portions of the bearing faces.
3. Spark gap apparatus, comprising a plurality of gap unit holders each having spring contact pieces to bear against opposite sides of a gap unit, said contact pieces of each holder being under tension to bear against each other to close the circuit at the holder when there is no gap unit in place therein, and electrical connections between the holders.
4. Spark gap apparatus, comprising a plurality of gap unit holders electrically connected in series, each holder being formed of a pair of spring conducting arms to bear against and support a gap unit and through which electrical connection is made to the opposite sides of the gap unit, said spring arms being under tension to move into engagement with each other and close the circuit across the holder when there is no gap unit in position in the holder.
5. Spark gap apparatus, comprising a plurality of gap unit holders each formed of a pair of spring conducting arms to bear against and support a gap unit and through which electrical connection is made to the opposite sides of the gap unit, the spring arms of each holder being under tension to move into engagement with each other and close the circuit across the holder when there is no gap unit in position in the holder, a terminal connected to the outer arm of each end holder and other terminals connected each to the adjacent arms of two adjoining holders, and contact means for making contact with said terminals to connect the holders in the circuit, said contact means being adjustable for varying the number of gap holders connected in the circuit.
6. Spark gap apparatus, comprising a plurality of gap unit holders each formed of a pair of spring conducting arms to bear against and support a gap unit and through which electrical connection is made to the opposite sides of the gap unit, the spring arms of each holder being under tension to move into engagement with each other and close the circuit across the holder when there is no gap unit in position in the holder, a terminal connected to the outer arm of each end holder and other terminals connected each to the adjacent arms of two adjoining holders, and contact means for making contact with said terminals to connect the holders in the circuit, said contact means being adjustable for varying the number of gap holders connected in the circuit and for connecting in the circuit any desired series of the gap holders.
7. Spark gap apparatus, comprising a plurality of gap unit holders, a plurality of terminals through which connections may be made for connecting different numbers of said holders in circuit, contact members for making circuit connections to said terminals, coaxial shafts mounted one within the other, connections between said shafts and said contact members, and means for turning said shafts either together or one relatively to the other for moving said contact members relatively to said terminals to vary the number of the gap holders connected in the circuit and for connecting in the circuit any desired series of the gap holders.
8. Spark gap apparatus, comprising a support, a plurality of gap unit holders mounted on the front side of the support, a plurality of terminals mounted on the rear side of the support through which connections may be made for connecting different numbers of the gap unit holders in the circuit, coaxial operating shafts mounted one within the other and extending from the front to the rear side of the support, contact members for making circuit connections to said terminals, connections for controlling the position of said contact members relatively to said terminals by the turning of said shafts, and operating means carried by said shafts at their forward ends whereby the shafts may be turned either together or one relatively to the other.
9. Spark gap apparatus, comprising a support, a plurality of gap unit holders mounted on the front side of the support, a plurality of contact terminals mounted on the rear side of the support through which connections may be made for connecting different numbers of the gap unit holders in the circuit, said terminals being arranged in a curve of constant radius, coaxial shafts mounted one within the other extending from the rear to the front side of the support, contact arms carried one by each of said shafts, a spring contact piece carried by each of said arms for making contact with said terminals, and hand pieces carried by said shafts at their forward ends whereby said shafts may be turned separately or one relatively to the other, said terminals and said contact pieces being formed with coacting positioning faces whereby the proper positioning of the contact pieces with relation to any terminals will be aided and will be manually indicated to the operator.
10. Spark gap apparatus, comprising a plurality of gap unit holders, a plurality of terminals through which connections may be made for connecting different numbers of said holders in circuit, contact members for making circuit connections to said terminals, coaxial shafts mounted one within the other, connections between said shafts and said contact members, and means for turning said shafts either together or one relatively to the other for moving said contact members relatively to said terminals to vary the number of the gap holders connected in the circuit and for connecting in the circuit any desired series of the gap holders.

- made for connecting different numbers of contact terminals through which connections said holders in circuit, said terminals being arranged in a curve of constant radius, contact arms mounted to turn on a common axis and each having a contact part for making contact with said terminals, and means for turning said arms either together or one relatively to the other to connect in the circuit any desired series of said holders or to vary 10 the number of said holders connected in the circuit. 11. Spark gap apparatus, comprising a plurality of gap unit holders, a plurality of terminals through which connections may be made for connecting different numbers of said holders in circuit, and a spring contact piece movable with relation to the terminals for varying the number of holders connected in the circuit, said terminals and said contact piece being formed with co-acting position faces permitting a forward movement of the contact piece under the pressure of its spring when it is positioned with respect to any one of the contact terminals, said parts being formed to prevent such forward movement of the contact piece in any intermediate position between adjacent terminals. 12. Spark gap apparatus, comprising a plurality of gap unit holders, a plurality of terminals through which connections may be made for connecting different numbers of holders in circuit, said terminals being spaced at approximately equal distances apart in a line or series, and a spring-pressed contact piece movable relatively to the line or series of terminals, said terminals and said contact piece being formed one with a convex contact face and the other with a concave contact face, and the contact piece having bearing portions at opposite sides of its contact face so formed that the bearing portion on one side of its contact face will, when the contact piece is being moved from one terminal to an adjacent terminal, come into engagement with the adjacent terminal while the contact piece is held pressed back against the pressure of its spring by the engagement of its other bearing portion with the terminal from which it is being moved. 13. Spark gap apparatus, comprising a plurality of gap unit holders, a plurality of contact terminals through which connections may be made for connecting different numbers of the gap unit holders in the circuit, hand operated circuit controlling means adjustable to vary the number of holders connected in the circuit and for connecting any desired series of the holders in the circuit, said means including means for manually indicating the contact making positions thereof, and means for indicating visually the number of holders connected in the circuit. 14. Spark gap apparatus, comprising a plurality of gap unit holders, a plurality of

- may be made for connecting different numbers of the holders in the circuit, contact members for making circuit connections to said terminals, means for moving said contact members relatively to said terminals comprising hand pieces movable together or relatively to each other, and a part mounted to move with one of said hand pieces and marked to indicate according to the relative position of the hand pieces the number of holders connected in the circuit. 15. Spark gap apparatus, comprising a plurality of gap unit holders, circuit controlling means for selectively connecting said gap unit holders in the circuit comprising members movable relatively to each other to vary the number of holders connected in the circuit and movable together for connecting in the circuit any desired series of said holders, hand pieces mounted to turn on a common axis and by the turning movement of which the position of said members may be adjusted, and a disc mounted to move with one of said hand pieces and marked to indicate according to the relative position of the hand pieces the number of holders connected in the circuit. 16. Spark gap apparatus, comprising a plurality of gap unit holders, a plurality of contact terminals through which connections may be made for connecting different numbers of the holders in the circuit, contact members for making circuit connections to said terminals, coaxial shafts mounted one within the other, connections for controlling the position of said contact members relatively to said terminals by the turning of said shafts, and hand wheels carried one by each of said shafts at one end thereof and mounted close together to permit them to be grasped and turned together or to be turned separately, one of said hand wheels having number markings associated therewith, and the other hand wheel having an indicator associated therewith, whereby the number of holders connected in the circuit will be indicated according to the relative positions of the hand wheels. 17. Spark gap apparatus, comprising a supporting plate of insulating material, a plurality of gap unit holders mounted on the front side of the supporting plate, a plurality of terminals mounted on the rear side of the supporting plate through which connections may be made for connecting different numbers of the gap unit holders in the circuit, said terminals being arranged in a curve of constant radius, coaxial shafts of non-conducting material mounted one within the other extending through the supporting plate, a contact arm carried by each of said shafts having a contact part for making contact with said terminals, a circuit connection directly to the contact arm

- carried by the inner shaft, a metal sleeve on the outer shaft to which the contact arm carried by the outer shaft is connected, a metal bearing ring mounted on the supporting plate through which the outer shaft extends and in which said sleeve is journaled, and a circuit connection to said bearing ring at the front side of said supporting plate. 50
18. Spark gap apparatus, comprising a plurality of gap units having electrode plates the outer faces of which are formed with parallel ribs providing an extended heat dissipating surface, the gap units being mounted in a horizontal row in which each unit stands in vertical position flatwise to adjacent units with its heat dissipating ribs extending vertically and in which the units are spaced apart to permit an upward flow of air between them. 55
19. A spark gap unit, comprising a pair of electrode plates assembled together flatwise and having sparking faces on their opposed inner sides, the outer surface of the plates on the sides opposite the sparking faces being formed with parallel ribs to provide an extended heat dissipating surface. 60
20. In a radio transmitting set, the combination with an instrument board, of a supporting plate removably secured in position in register with an opening in the instrument board, a plurality of gap unit holders on the front side of the supporting plate, circuit controlling means for variably connecting said gap unit holders in the circuit mounted on the rear side of said supporting plate, and operating means for said circuit controlling means mounted on the front side of said supporting plate. 65
21. Spark gap apparatus, comprising a hinged support, a plurality of gap unit holders mounted on the front side of the support, circuit controlling means for variably connecting said gap unit holders in the circuit mounted on the rear side of the support, operating means for said circuit controlling means mounted on the front side of the support, means for holding the support in operative position and for releasing the support to permit it to be turned into position for access to the rear side thereof, and means for automatically connecting the spark gap apparatus in the circuit when the support is moved into its operative position. 70
22. Spark gap apparatus, comprising a hinged support, a plurality of gap unit holders mounted on the front side of the support, circuit controlling means for variably connecting said gap unit holders in the circuit mounted on the rear side of the support, operating means for said circuit controlling means mounted on the front side of the support, means for holding the support in operative position and for releasing the support to permit it to be turned into position for access to the rear side thereof, and means for automatically connecting the spark gap apparatus in the circuit when the support is moved into its operative position. 75
23. Quenched spark gap apparatus comprising a bar of insulating material, a series of metal contact springs secured thereto in spaced arrangement, the fixed ends of successive pairs of adjacent springs being permanently connected electrically, and the free ends of adjacent springs being movable by their resiliency into contact with each other in pairs alternating with the pairs of connected fixed ends, in combination with gap units insertable between the pairs of resiliently contacting spring ends to separate the same and to be resiliently held thereby. 80
- In testimony whereof I have hereunto set my hand in the presence of two subscribing witnesses. 85
